CLAIM

The ornamental design for a housing for a handset base, as shown and described.

DESCRIPTION

FIG. 1 is a top, front and right side perspective view of the housing for a telephone base embodying our new design;

FIG. 2 is a top, rear and left side perspective view thereof;

FIG. 3 is a top plan view thereof;

FIG. 4 is a bottom plan view thereof;

FIG. 5 is a right side elevation thereof; and,

FIG. 6 is a left side elevation thereof.

The broken line showings of buttons at the side in FIGS. 1 and 3-5 are for illustrative purposes only.

*FIG. 1**FIG. 2**FIG. 3*

FIG. 4

FIG. 5

FIG. 6
